PROCESSING OF HEAVY GAS OILS

Charles E. Hemminger, Westfield, N. J., assignor
to Standard Oil Development Company, a cor-
poration of Delaware

Application August 17, 1940, Serial No. 353,039

3. Claims. (Cl. 196—53)

The present invention relates to improvements in the art of refining petroleum hydrocarbons. More particularly, this invention relates to improvements in preparing a charging stock which may be treated in thermal oil cracking equipment with advantage, as will hereinafter more fully and at large appear.

One of the advantages of catalytic cracking of gas oils to produce gasoline is the capability of the process to treat gas oil of high end boiling point. In the thermal cracking of gas oil, it is not practical, or, at least there are serious disadvantages in treating a gas oil having a boiling range extending substantially above 700° F. These disadvantages are: (1) In a vapor phase thermal cracking operation where 25% of the feed stock boils above say 700° F., such excessive amounts of coke are formed in a short time as to render the process entirely non-feasible commercially; and (2) in liquid phase thermal cracking, regardless of the boiling range of the feed stock, the gasoline produced has a low octane rating.

One object of this present invention is to transform chemically a gas oil of which about 95% boils above 700° F. in the presence of a cracking catalyst such as an acid treated clay, under conditions such that a relatively small amount of hydrocarbons boiling within the gasoline range are produced and wherein the product primarily produced is a gas oil boiling substantially within the range of from about 400° F. to 700° F. The gas oil thus produced after separation from gasoline and from the normally gaseous constituents, may be used as a heating oil or may be conveniently and with certain advantages cracked in vapor phase to produce gasoline of high octane rating.

Another object of my invention is to convert a gas oil boiling within the range of from about 700° F. to 1050° F. to a gas oil boiling within the range of from about 400° F. to 700° F., which latter gas oil is a satisfactory cracking feed stock for a liquid phase cracking operation, where a high octane rating gasoline is not desired, since the lower boiling gas oil gives much higher conversions to gasoline per passage through the cracking operation, as well as higher yields of gasoline, than the higher boiling range gas oil.

Another object of the present invention involves hydrogenating a gas oil fraction boiling within the range of from about 400° F. to 700° F. produced catalytically from a gas oil of higher boiling range to improve its quality as a thermal cracking stock.

Other and further objects of my invention will

appear from the following more detailed description.

To the accomplishment of the foregoing and related ends, I provide a process and a suitable apparatus for carrying out the said process, in which a gas oil of relatively high boiling range is catalytically treated to produce a gas oil of relatively lower boiling range, and, in particular, being rich in fractions boiling below 700° F., and, if desired, thereafter subjecting the formed gas oil to hydrogenation followed by thermal cracking to produce gasoline, or the gas oil produced may be employed as a heating oil.

My invention will be best understood by setting forth a concrete example and the manner in which it may be carried out.

In the drawing, the single figure represents diagrammatically a suitable apparatus in which my process may be carried out.

Referring to the accompanying drawing in detail, a gas oil boiling in the range of from about 700° F. to 1050° F. is introduced into the system through line 1 and thence discharged into the pump 2, thereafter fed into a fired coil 3 disposed in a furnace setting 4. In the coil 3, the gas oil is heated to a temperature of about 800° F. to 950° F., whereupon it is discharged into tar separator 6 where, in the presence of steam or other diluents, the larger portion of the oil is vaporized, leaving about 3% to 10% pitch or tar based on the charging stock to be removed through line 8, the vapors discharging through line 7 into a catalytic conversion chamber 9 containing preferably a plurality of spaced apart beds of catalytic material such as an acid treated clay, the said beds being supported on foraminous trays T—1, T—2, T—3, and T—4. The vaporized hydrocarbons pass in series through the several trays of catalyst and are then withdrawn overhead through line 10. The shell of chamber 9 is preferably lagged with heat insulating material, and the temperature of the vapors entering the said chamber is preferably sufficiently high so that the heat loss caused by the endothermic nature of the cracking operation will not cause a temperature drop in the uppermost tray T—1 below that at which active cracking may occur. Ordinarily, an inlet temperature to the chamber 9 of 850° F. to 925° F. gives best results. The pressure existing in chamber 9 may be from 1-10 atmospheres, but best results are obtained by operating at about 10 lbs. per square inch gauge. The linear velocity of the oil vapors passing through the catalyst is sufficiently high so that only 5% to 15% gasoline by volume, based on the

gas oil fed to the system, is formed. This is accomplished by restricting the time the vapors are resident in the reactor 9 to from about 2 to 30 seconds.

The cracked vapors are withdrawn through line 10 and then discharged into a fractionating tower 14. The main product withdrawn from tower 14 after fractionation is a gas oil fraction boiling within the range of from 400° F. to 700° F. which is withdrawn through line 18. In addition to gas oil withdrawn through line 18, a heavy gas oil boiling in the range of from about 700° F. to 900° F. is withdrawn through line 19, but this fraction usually contains tar and aromatics and preferably is rejected from the system. A light gas oil, say a cut boiling within the relatively narrow range of from about 400° F. to 500° F. may be withdrawn through line 20 and this cut may be used for any desired purpose. Preferably, however, all of the gas oil, except the bottoms withdrawn through 19, is withdrawn through conduit 18. A gasoline fraction is withdrawn from tower 14 through line 16, and normally gaseous hydrocarbons are withdrawn through line 17. The total amount of permanent gases and gasoline should not amount to more than 20% by weight of the original charging stock. The gasoline produced may be refined, stabilized and sent to storage in equipment not shown.

The gas oil fraction is preferably delivered through conduit 18, to a hydrogenation unit 21 where it contacts hydrogen delivered to the hydrogenation unit from some available means through conduit 22, and a suitable hydrogenation catalyst. The hydrogenation of the gas oil is preferably carried out at a temperature of about 700° F. to 900° F. and under a pressure of 10 to 200 atmospheres in the presence of a catalyst such as a mixture of equal parts by weight of nickel sulfide and tungsten sulfide, the amount of hydrogen being from about 12,000 to 15,000 cubic feet of hydrogen measured under standard conditions, per barrel of gas oil feed to the system. The feed rate of gas oil is preferably from 1 to 2 volumes of cold oil per volume of reactor per hour. The hydrogenated oil is then withdrawn from the hydrogenation unit through line 25 and passed into separator 27 where the hydrogen is separated from the oil and recycled through line 24 to line 22. The gas oil is withdrawn from separator 27, through conduit 28 carrying pressure reducing valve 29 and thence forced into fired coil 30.

In the coil the gas oil is heated to a temperature of from about 850° F. to 1050° F. while under a mild pressure, say 10 to 20 lbs. per square inch gauge pressure, whereupon the cracked product is delivered through conduit 31 to tar separator 32 where tar is withdrawn through pipe 33 while the vapors pass overhead through conduit 34 to a fractionating column 35. In this column, the oil is fractionated to yield a gasoline fraction which is withdrawn through line 36 and a heavier gas oil fraction which is withdrawn through line 38. The gasoline fraction in the form of vapors passes through a condensing coil 40 and thereafter, in liquid form, is discharged into a receiving drum 41, from which the gasoline may be recovered through line 42, while the normally gaseous fractions may be withdrawn through line

43. The fraction withdrawn through line 38 represents an unconverted gas oil, and this oil may be recycled to line 1 for further catalytic treatment or passed through line 39 to line 28 for further thermal treatment in cracking coil 30. As an alternative procedure, I may discharge the gas oil through pipe 18 directly into coil 30 through lines 50 and 29 thus by-passing the hydrogenation step. Also I may remove gas oil 10 in line 18 from the system through draw-off pipe 51.

Some of the obvious modifications of my process include employing a powdered catalyst suspended in the gas oil during the cracking of the charging stock. Thus powdered catalyst may be dispersed or suspended in the vapors in line 7 and conducted to a reaction zone maintained under the same or similar conditions as hereinbefore set forth in connection with the description of the operation 15 carried out in reactor 9. Of course, in this modification tray type reactor 9 would be replaced by a coil or a drum. Also I may use instead of acid treated clay, a catalyst composed of silica, alumina gels, mixtures or compositions, or I may use 20 silica gel mixed with magnesium oxide gel.

While I have described a process hereinbefore which includes hydrogenation of the gas oil produced catalytically, followed by thermal cracking to form gasoline, I wish to point out that my invention is not limited to the said process but in 30 its broadest aspect my process involves converting a heavy gas oil say one boiling in the range of from about 700° F. to 900° F. or 1050° F. to a gas oil boiling from about 400° F. to 700° F. which 35 may be used for any purpose, i. e. as a cracking stock in a gasoline producing operation or as a heating oil.

Numerous modifications of my invention will be readily understood by those skilled in this 40 particular art.

What I claim is:

1. The method of preparing a lower boiling gas oil particularly suitable for thermal cracking from a higher boiling gas oil comprising at least 45 95% of hydrocarbons boiling above 700° F. and below 1,050° F., which comprises heating the higher boiling gas oil to a temperature between 800 and 950° F., introducing the heated gas oil into a tar separator wherein the major proportion 50 of the gas oil is vaporized, subjecting the vapors so obtained to catalytic cracking in a reaction zone in which they are resident for about 2 to 30 seconds, to produce between 5 and 15% by volume of gasoline based on the gas oil, and 55 recovering from the products of catalytic cracking a fraction boiling between 400 and 700° F.

2. Process according to claim 1 in which the fraction boiling between 400 and 700° F. segregated from the products of catalytic cracking is 60 subjected to non-destructive hydrogenation, the hydrogenated product is fractionated to produce a gasoline fraction and a heavier fraction, and a heavier fraction is returned to the stage in which the higher boiling gas oil is heated.

3. Process according to claim 1, in which the products from the catalytic cracking step include a gas oil of boiling range between 400 and 500° F., and the total amount of permanent gases and gasoline produced in the catalytic cracking step 65 do not exceed 20% by weight of the higher boiling gas oil.

CHARLES E. HEMMINGER.
